RUPTURABLE APPARATUS FOR SEALING FLUID SYSTEM ELEMENTS

Filed July 29, 1949

UNITED STATES PATENT OFFICE

2,667,760

RUPTURABLE APPARATUS FOR SEALING
FLUID SYSTEM ELEMENTS

Charles L. Curtis, Pasco, Ohio, assignor to Cope-
land Refrigeration Corporation, Sidney, Ohio,
a corporation of Michigan

Application July 29, 1949, Serial No. 107,524

11 Claims. (Cl. 62—115)

1

This invention relates generally to sealing means, and is particularly adapted among other uses in connection with the manufacture and assembly of refrigerating mechanisms.

An object of this invention is to provide a simple sealing means for subassemblies of refrigeration mechanisms whereby they may be shipped in a hermetically sealed condition and later assembled together with a minimum of effort to complete the refrigerating apparatus.

Another object of such invention is to provide such a sealing means which may easily be ruptured and rendered ineffective to seal after assembly of the refrigerating apparatus.

Another object of this invention is to provide such a sealing means which may be ruptured subsequent to assembly without requiring any opening of the assembled system.

Another object of this invention is to provide a combined valve and seal rupturer.

Another object of this invention is to provide a three-way valve which may have its two outlet ports sealed at the same time for shipping purposes, one of the ports being sealed by means of a frangible seal which is ruptured upon movement of the valve member in a direction to unseal the port closed by the valve member.

Other objects of this invention will be apparent from the specification, the appended claims and the drawings, in which drawings,

Figure 1 is a diagrammatic view of a portion of two elements of a refrigerating system, prior to assembly and embodying the invention;

Fig. 2 is a partial view similar to Fig. 1 but showing the elements of Fig. 1 in an assembled relation;

Fig. 3 is an enlarged view of a section within the circle "A" of Fig. 2;

Fig. 4 is a view similar to Fig. 3 but showing the sealing means ruptured; and,

Fig. 5 is an enlarged view of the elements within the circle "B" of Fig. 1.

Referring to the drawings by characters of reference, the numeral 1 indicates generally a condensing unit comprising a motor compressor unit 2 having a discharge service valve 4 connected by means of the conduit 6 to a heat extracting unit or condenser 8. The outlet of the condenser 8 is connected by means of conduit 10 to a liquid line valve 12. The numeral 14

2

designates a fan motor for driving air through the condenser 8.

An inlet service valve 16 for the unit 2 has a pair of valve controlled passageways 18 and 20 communicatively connected with each other and with a common passageway 22 in continual open communication with the suction side of the condenser compressor unit 2. The outwardly open end of passageway 18 is located within a male fitting 24 which is externally threaded as at 26 for reception of a cap nut 28 by which the flared end 30 of a suction conduit 32 is secured to a tapered end portion 34 of the male fitting 24. The other end of the conduit 32 is connected to the outlet header 36 of an evaporator 38. The inlet header 40 of evaporator 38 is connected by conduit 42 to the liquid line valve 12. The conduit or tube 42 may be of small bore whereby its innate resistance to flow of fluid will meter the refrigerant supplied to the condenser 38 from the condensing unit 1. If desired, the tube 42 could be of larger bore and a usual feed device such as an expansion valve could be used, if desired.

Upon initial manufacture of the service valve 16, its passageway 18 is sealed closed adjacent its outwardly open end by means of a cup-shaped frangible seal 60 which is suitably sealed in fluid-tight relation thereto. The adjacent end of the tubing 32 is closed by means of a frangible diaphragm 62 sealed within the bore of tube 32 adjacent the inner end of the flare 30. The service valve 16 has a valve stem 64 threaded as at 66 for threaded engagement with internal threads 70 of body 68 to provide for reciprocal movement of the stem 64 relative to the valve body 68. Suitable packing 72 and a packing gland 74 is provided to prevent flow of fluid along the valve stem 66 outwardly of the casing or valve body 68. The neck portion of the valve body 68 is externally threaded as at 76 for reception of the usual stem capping nut 77 which may be screwed thereon when the valve stem 66 has been set in the desired position.

The valve stem 64 is provided with oppositely facing frusto-conical surfaces 78 and 80 which engage respectively with valve ports 82 and 84 for preventing flow of fluid through the valve passageway 18 or the valve passageway 20. The valve stem 64 is further provided with an exten-

sion 86 having on its forward end a seal piercing element 88 which resembles the cutting end of a fluted drill. Upon inward movement of the valve stem 66, the piercing element 88 engages the seals 60 and 62 whereby they are ruptured and further movement of the piercing head 88 causes these seals to be folded in telescopic arrangement with the inner wall of the conduit 32 as shown in Fig. 4.

Similarly, the liquid line valve 12 is connected 10 to the tubes 10 and 42 and is provided with a valve stem 90 having a port engaging surface 92 cooperable with a valve port 93 for preventing flow of fluid through the valve outlet passageway 94. The stem 90 is provided with an extension 15 95 which has on its forward end a seal piercing member 96 similar to the element 88 which is adapted to pierce a cup-shaped seal 97 which is sealed within and closes the outlet passageway 94 of the liquid valve 12. The inward movement 20 of the stem 90 also moves the member 96 to pierce or rupture a seal 98 arranged in the end portion of the tubing 42 similarly as was the seal 62 in the tubing 32. Such inward movement 25 of the valve stem 90 moves the piercing member 96 to pierce the seals 97 and 98 and fold them outward in telescopic arrangement against the interior surface of the tube 44 similarly to the telescopic arrangement of the seals 60 and 62 within the tubing 32 as shown in Fig. 4.

It will be apparent that with the valve stem 66 of the valve 16 in its position as shown in Fig. 3 with the seat engaging surface 80 in engagement with the valve port 84, and prior to rupturing of the seal 60, both the outlets 18 and 20 will be closed against leakage of fluid outwardly of the valve from the common passageway 22. Also, the ends of the conduits 32 and 42 will be sealed against flow of fluid externally into or out of these conduits. After assembly of the conduits to the valves as by the cap nuts 28 and 48, the valve stems 66 or 90 may be rotated to move them inwardly into their respective valve bodies for piercing or rupturing the seal and for folding the seals to provide a fluid flow passageway between the valves and the conduits with which they are connected. Subsequent to rupturing of the seals, the valve stems 66 and 90 may be moved back to the position shown in Figs. 3 and 5, whereby the valves are communicatively connected with the conduits with which they are associated. The valves 12 and 16 subsequent to rupturing of the respective seals, may be operated in the usual and conventional manner.

It is believed that it will be apparent from the foregoing that by the use of applicant's invention, various refrigerating components of a complete apparatus may be shipped, disassembled from one another and then assembled at any desired time without a laborious process of removing any foreign matter such as moisture, air, etc. which may have found its way into the system's component parts should they be shipped unsealed or admitted thereto if it were necessary to unseal the component parts prior to assembly into a complete apparatus.

Generally it is considered desirable to ship the evaporators 38 with their associated conduits 32 and 42 in a completely evacuated and dehydrated condition while it is usually desired to ship the condensing unit 1 fully charged so that when assembled with the evaporator 38 and the seal ruptured, the system is ready to function. It will be apparent, however, that if desired the evaporator 38 could be precharged with a normal

desired charge of refrigerant and the condensing unit 1 be conditioned so that when the evaporator 32 is connected thereto and the seals 60, 62, 97 and 98 ruptured, as described above, the system will be ready to operate.

What is claimed and is desired to be secured by United States Letters Patent is as follows:

1. In an assembled fluid conveying apparatus, a valve body having a pair of openings connected by means of a passageway, said passageway being provided with a valve port aligned with one of said openings, a valve stem concentrically positioned relative to said one opening and said port, a port closing member carried by said stem and engageable with said port to restrict flow of fluid therethrough, a fluid conveying conduit having an internal passageway opening outwardly through one end thereof, means adapted to secure said conduit one end to said body with said conduit passageway in alignment with said body one opening, a first frangible member sealing said conduit passageway closely adjacent said conduit one end, a second cup shaped frangible member sealing said body one opening with said second member facing inwardly into said body passageway, a rupturing and forming element carried by said valve stem forwardly of said port closing member and operable upon movement of said port closing member toward port closing position to extend into said conduit to rupture said frangible members and to fold said frangible members in telescopic arrangement against the wall of said conduit passageway.

2. In combination a pair of refrigerating system elements, each of said elements having an opening through a wall thereof, said openings being adapted to be arranged in juxtaposition to permit flow of refrigerant between said elements, attaching means clampingly securing said walls in contacting engagement with each other, each said element being provided with a frangible seal located adjacent its said wall and individually closing its respective opening, said seals being adjacent outermost portions of the engaging portions of said elements whereby when said walls are in engagement the space between said seals is substantially eliminated, and rupturing means carried within one of said elements on the side of said one element seal away from the other of said seals for rupturing both said seals to initiate fluid flow between said elements.

3. In a sub-assembly for a refrigerating system, a refrigerating system component comprising means forming a refrigerant containing structure having an inlet and an outlet connection adapted to be coupled to another portion of the refrigerating system, at least one of said connections comprising a portion of fluid conveying conduit having an end wall adapted to be connected to a mating element in such system portion, a frangible member carried by and sealed in fluid tight relation to said conduit closely adjacent said end wall to prevent undesired ingress and egress of fluid, said frangible member being rupturable to place said conduit in open communication with such mating element, and means closing the other of said connections against undesired ingress and egress of fluid through said other connection.

4. In a sub-assembly for a refrigerating system, an evaporator, an inlet conduit and an outlet conduit secured to said evaporator in fluid flow communication therewith, said conduits each having a free end portion adapted to be connected to another portion of a refrigerating

system, a pair of frangible diaphragm members, said frangible members being individually secured in fluidtight relation to each of said conduits closely adjacent the end wall of said conduits at said free end portion.

5. In a sub-assembly for a refrigerating system, a refrigerating system component comprising means forming a refrigerant containing structure having an inlet and an outlet connection adapted to be coupled to another portion of the refrigerating system, at least one of said connections comprising a body having an end wall adapted to be connected to a mating element in such system portion, a frangible member carried by and sealed in fluidtight relation to said body closely adjacent said end wall to prevent undesired ingress and egress of fluid through said one connection, said frangible member being rupturable to place said one connection in communication with such system portion, means closing the other of said connections against undesired ingress and egress of fluid through said other connection, and rupturing means carried within said body for rupturing said frangible member.

6. A seal for a fluid system comprising a length of tubing terminating in an outwardly flared end portion, a frangible sealing member fixed within said tubing at a position spaced from the outer end of said flared end portion, and an attaching member surrounding said flared end portion and adapted to be connected to a mating portion of said system to hold said flared end portion in fluidtight relationship with said mating portion.

7. A sealed fluid system comprising a length of tubing terminating in an outwardly flared end portion, a body member having a fluid passageway opening outwardly through a wall thereof, an attaching member surrounding said flared portion and connected to said body member whereby said flared portion and said passageway are aligned substantially co-axially, said attaching member having a shoulder engageable with said flared portion to hold said flared portion in fluidtight relation with said body member, a first frangible sealing member fixed within said tubing at a position spaced from the outer end of said flared portion, a second frangible member fixed within said passageway at a position adjacent the outer end thereof whereby when said flared portion and said body member are in engagement, the space between said seals is substantially eliminated, and rupturing means carried within said body on the side of said second frangible member away from said first frangible member for rupturing both said frangible members to initiate fluid flow through said tubing and said passageway.

8. In a connection for a fluid system, the combination comprising a body member having a fluid passageway opening outwardly through a wall thereof, said wall being formed with a shoulder surrounding the opening of said passageway therethrough, a tubular element having an outwardly flared end portion, an attaching member surrounding said flared portion and connected to said body member whereby said flared portion and said passageway are aligned substantially co-axially, said attaching member having a shoulder engageable with said flared portion to hold said flared portion in fluidtight relationship with the shoulder on said body member, a first frangible seal fixed within said tubular element at a position spaced from the outer end of said flared portion, a second frangible seal

fixed within the passageway of said body adjacent the outer end thereof whereby when said flared portion and the shoulder on said body member are in engagement the space between said seals is substantially eliminated, and rupturing means carried within said body on the side of said second seal away from said first seal for rupturing both of said seals to initiate fluid flow through said tubular element and said passageway.

9. In a connection for a fluid system, the combination comprising a body member having a fluid passageway opening outwardly through a wall thereof, said wall being formed with a shoulder surrounding the opening of said passageway therethrough, a tubular element having an outwardly flared end portion, an attaching member surrounding said flared portion and threadably connected to said body member whereby said flared portion and said passageway are aligned substantially co-axially, said attaching member having a shoulder engageable with said flared portion to hold said flared portion in fluidtight relationship with the shoulder on said body member, a first frangible seal fixed within said tubular element at a position spaced from the outer end of said flared portion, a second frangible seal fixed within the passageway of said body adjacent the outer end thereof whereby when said flared portion and said shoulder on said body member are in engagement the space between said seals is substantially eliminated, a rupturing member mounted in said passageway, said rupturing member having a portion thereof located exteriorly of said body member and a rupturing portion within said passageway, said rupturing member being movable axially of said passageway in response to force applied to said exterior portion so as to rupture both of said frangible seals to initiate fluid flow through said tubular element and said passageway.

10. A connection for a fluid system comprising a length of tubing terminating in an outwardly flared end portion, a first frangible seal fixed within said tubing adjacent the inner end of said flared portion, a body member having an internal passageway opening outwardly through a wall thereof, said wall being provided with a seating surface surrounding the opening of said passageway therethrough and against which said flared portion seats, a second frangible seal fixed to said body member in said passageway, the outer surface of said second frangible seal being substantially co-planar with the outer surface of the portion of said wall adjacent said passageway opening, means carried by said tubing for connecting said flared end portion to said seating surface of said body member, and rupturing means mounted in said passageway and operable externally thereof for rupturing both of said frangible seals.

11. A connection for a fluid system comprising a length of tubing terminating in an outwardly flared end portion, a first frangible seal fixed within said tubing adjacent the inner end of said flared portion, a body member having an internal passageway opening through a wall thereof and an internal valve seat surrounding said passageway, said wall being provided with an external seating surface against which said flared portion seats, a second frangible seal fixed to said body member in said passageway, the outer surface of said second frangible seal being substantially co-planar with the outer surface of the portion of said wall adjacent said passageway

opening, means carried by said tubing for connecting said flared end portion to said seating surface of said body member, and a rupturing member mounted in said passageway and operable externally thereof for rupturing both of said frangible seals, said rupturing member having a valve seating element adapted to engage said internal valve seat subsequent to the rupturing of said frangible seals.
